GRINDING WHEEL DRESSING MECHANISM

Warren S. Omwake, Waynesboro, Pa., assignor to Landis Machine Company, Waynesboro, Pa., a corporation of Pennsylvania

Application December 12, 1956, Serial No. 627,909

7 Claims. (Cl. 125—11)

This invention relates to mechanisms for dressing grinding wheels and more particularly to such mechanisms for generating multiple profiles on grinding wheels.

Heretofore the operation of dressing a grinding wheel by traversing a diamond across its working surface during rotation of the wheel has been found to be most effective and economical when used on wheels for grinding simple profiles. Mechanisms for performing such operations have taken a wide variety of forms. A mechanism including a template duplicating the contour to be formed on the grinding wheel has generally been used when a more complex operation was involved, such as forming the profiles of numerous annular ridges on a wheel for grinding screw threads. In such dressing machines a slide carrying the diamond tool and a template follower traverses both the grinding wheel and the template simultaneously. Such a mechanism is shown, for example, in the United States Patent No. 2,447,503 issued August 24, 1948 to J. G. Harper et al.

Certain limitations as to field of use are inherent in the structure of such devices. Relative rectilinear movement between the template and follower in a direction parallel to the grinding wheel axis creates a camming relationship between template and follower to cause the follower and the attached diamond tool to move in a direction perpendicular to the grinding wheel axis. The surfaces on the template which cause such movement of the tool correspond to the flanks of the thread profile to be formed on the grinding wheel. In accordance with well known cam design principles the flank angle of the thread, that is, the angle between the flank of the thread and a line perpendicular to the axis thereof will have a certain minimum value. If the flank angle is too steep the axial component of the force exerted by the template upon the follower will be great enough to cause the latter to stick momentarily and to have an irregular and jerky radial movement or no radial movement at all.

Despite the use of anti-friction bearings to make the radially-moving, tool-carrying slide virtually frictionless, it is generally recognized that these considerations prohibit the use of this type of dresser mechanism on trapezoidal, Acme and worm threads whose flank angles range from 10 to 20 degrees. Prior attempts to overcome that limitation have led to the construction of a variety of devices all of which are extremely complex, expensive, delicate, slow and subject to error.

In the device of the present invention, which overcomes the above-stated disadvantages of prior machines, the relative rectilinear motion between template and follower is a number of times faster than the parallel relative motion between the dressing tool and the grinding wheel. The differential in traverse velocity is effected by a ratio lever mechanism. The radial infeed of the dressing tool is effected by the template directly so that the travel of the dressing tool in that direction is exactly equal to the depth of the profile formed on the template. Thus while the dimensions of the template profile in the direction perpendicular to the grinding wheel axis

2

are equal to the dimensions of the wheel profile in that direction, the dimensions of the template profile in the transverse or axial direction are a multiple of the corresponding dimensions of the profile to be produced on the grinding wheel. Consequently, if the profile is that of a screw thread, the depth of the thread is maintained on the template while the pitch thereof is multiplied. The flank angles of the thread profile are accordingly increased on the template, permitting the use of a simple template-and-follower type of dressing device to form profiles on the grinding wheel which could not be formed with prior mechanisms of comparable cost and simplicity.

According to a further feature of the invention, the ratio lever mechanism may be altered selectively to obtain various magnifications of the transverse movement between template and follower or to eliminate such magnification if desired.

It is therefore an object of the invention to provide a grinding wheel dressing mechanism of the template-controlled type for the formation of profiles having steep flank angles.

Another object of the invention is to provide such mechanism having a slide carrying a tool and a template capable of transverse and radial movement relative to a grinding wheel and of movement in the same directions relative to the controlling follower or system, in which only the transverse relative movement of the slide and stylus is magnified with respect to the transverse movement of the slide relative to the grinding wheel.

A further object is to provide mechanism as above described in which the transverse movement of the stylus relative to the template is magnified proportionately by means of a ratio lever device.

A still further object of the invention is to provide mechanism as described above in which the dimensions of the controlling template are magnified with respect to the grinding wheel profile in the transverse direction only.

Another object is to provide means for selectively varying the degree of magnification of the above-mentioned transverse movement or for eliminating the magnification as desired.

A further object of the invention is to provide means for carrying out the dressing operation automatically with the mechanism described above.

Other objects and advantages will be apparent from the following description of an exemplary embodiment of the invention and from the accompanying drawings, in which:

Figure 1 is a front elevation of a grinding wheel dressing mechanism constructed in accordance with the invention;

Figure 2 is a side elevation of the mechanism as seen from the left hand side of Figure 1;

Figure 3 is a partial top plan view of the mechanism;

Figure 4 is a vertical sectional view taken substantially along line 4—4 of Figure 1;

Figure 5 is a partial sectional view taken substantially along line 5—5 of Figure 4, with the stylus, stylus supporting bracket and cover removed;

Figure 6 is a horizontal sectional view taken substantially along line 6—6 of Figure 4;

Figure 7 is a partial rear elevation showing the device for setting the angular position of the dresser slides;

Figure 8 is a partial sectional view taken along line 8—8 of Figure 1;

Figure 9 is a partial front elevation similar to a portion of Figure 1, but with certain parts removed from the mechanism;

Figure 10 is a top plan view of the parts shown in Figure 9;

Figure 11 is a partial section taken along line 11—11 of Figure 1;

Figure 12 is a partial section taken along line 12—12 of Figure 5;

Figure 13 is a partial section taken along line 13—13 of Figure 1 and Figure 5;

Figure 14 is a partial section taken along line 14—14 of Figure 1;

Figure 15 is a partial section taken along line 15—15 of Figure 6; and

Figure 16 is a partial section taken along line 16—16 of Figure 15.

As shown in Figures 1—6 the entire dresser mechanism is mounted on and supported by a base member 30 which may be secured to the bed of a thread grinding machine, for example, in well-known manner. A vertically arranged frame 32, generally circular in outline and strengthened by webs 34, is cast integrally with the base member 30. Referring particularly to Figures 4 and 6, the frame 32 is provided with a circular finished surface 36 facing the grinding wheel W. A bracket 38 is held firmly against the surface 36 by means of a headed stud 40 which is journaled through the vertical rear wall of the bracket 38 and the adjacent frame 32, an integral boss 42 being formed on the latter to provide sufficient bearing area for the stud 40. The rear end of boss 42 is closed by a cap 44 and a cap screw 46 is passed through the cap 44 and threaded into the interior of the stud 40 to retain the parts in position.

The stud 40 serves as a pivot about which the bracket carrying the dressing mechanism may be rotated when the screw 46 is loosened slightly. Thus the entire dressing mechanism may be adjustably tilted so that its movements are aligned with the axis of the grinding wheel W which is usually inclined to the helix angle of the thread being ground. The axis of the stud 40 should be aligned with the axis about which the grinding wheel is pivoted so that the relative movement between the dressing tool and the grinding wheel will be the same in all angularly adjusted positions thereof. A plurality of plugs 47, backed by springs 48 (Figure 4) may be installed in the boss 42 to press rearwardly against the cap 44 to prevent the bracket 38 from moving away from the surface 36 when the screw 46 is loosened for adjustment and thus prevent foreign matter from entering between the bracket 38 and the surface 36. After angular adjustment and during operation, the screw 46 is tightened and the bracket 38 is stationary relative to the base 30.

A means for accurately adjusting the bracket 38 angularly with respect to the frame 32 is shown in Figures 7 and 8 and includes a pin 50 pressed into the frame 32 and projecting from the rear surface thereof. A second pin 52, spaced angularly from the pin 50, is pressed into bracket 38, extends through an elongated slot 54 in the frame 32 and projects rearwardly therefrom coextensive with the pin 50. An adjusting screw 56 is threaded into the frame 32, extending into the slot 54 to abut the pin 52 tangentially with respect to the axis of the pivot stud 40. Rotation of the screw 56 will increase or decrease the distance between the pins 50 and 52 and thus finely adjust the bracket 38 angularly, relative to the frame 32. The distance between pins 50 and 52 necessary for any desired angular adjustment may be computed and tabulated in advance and may be measured as by means of micrometers. A coarse adjustment may be indicated by an angular scale 58 (Figure 2) inscribed on the periphery of the frame 32 cooperating with an index mark 60 similarly inscribed on the adjacent periphery of the bracket 38.

A slide base 62 is secured to the forward surface of the vertical portion of bracket 38 by means of screws 64 and a locating pin 66 (Figure 6). A slide assembly 68 is mounted on base 62 for movement parallel to the axis of the grinding wheel W. The slide 68 comprises a top plate 70 which extends beyond the slide base 62 on all

sides. A bottom plate 72, having substantially the same external dimensions as the top plate 70 but having its interior cut away to form a voided rectangle, surrounds the slide base 62. The bottom plate 72 is spaced rearwardly from the top plate 70 and along the sides of the slide base 62 the intervening space is occupied by a pair of bearing strips 74. The assembly is held together by means of screws 75 which pass through top plate 70 and bearing strips 74 and are threaded into the bottom plate 72 (Figures 4 and 12). The inwardly directed V-grooves of the strips 74 cooperate with similar outwardly-directed V-grooves formed in the sides of the slide base 62 to form a raceway for a number of bearing rollers 76 (Figures 15 and 16). The rollers 76 are restrained longitudinally by a pair of bearing retainers 78, one of which is disposed on each side of the slide base 62 and between that base and the adjacent bearing strip 74. A pin 80 may be pressed into the center of each bearing retainer 78, projecting on both sides into longitudinal slots 82 in the bearing strips 74 and the slide base 62 to limit the longitudinal movement of the bearing retainers.

As shown in Figure 6, the slide base 62 is cut away at 84 to accommodate the end portions of the bottom plate 72 in the reciprocal movement of the slide 68. Longitudinally, the top plate 70, bottom plate 72 and bearing strips 74 are of equal extent and are longer than the slide base 62 by an amount equal to the desired length of travel of the slide 68. The ends of the slide 68 are closed by a pair of end covers 86 which are attached to the top and bottom plates by means of screws 88. Protection of the interior of the slide against grinding dust and other foreign matter is obtained by a sealing plate 90 disposed between bottom plate 72 and the adjacent forward surface of the bracket 38. The sealing plate 90 has its central portion voided to surround closely the slide base 62 and a plurality of springs 92 (Figure 2) are mounted in bracket 38 to hold the plate 90 tightly against the bottom plate 72. Thus a unitary, dirt-proof and virtually frictionless slide 68 is mounted for sliding movement on the base 62.

Reciprocation of the slide 68 on its base 62 is effected by the following mechanism. A ledge 94 (Figures 4 and 5) is machined in the upper forward portion of the top plate 70 to form a seat for a bracket 96 (Figures 4, 9 and 10) which is secured to top plate 70 by means of screws 98. The bracket 96 projects above top plate 70 and this projecting portion is provided with rack teeth 100 for meshing engagement with a spur pinion 102. The pinion 102 is secured upon a vertically disposed shaft 104 by means of a pin 106. A portion 108 of the bracket 38 projects forwardly above the slide 68 and has a vertical through bore to receive spaced bushings 110 in which the shaft 104 is journaled. A washer 112 is inserted between the hub of pinion 102 and the bracket portion 108, which also comprises an upwardly facing cavity 113 having a boss 114 to support a flange 116, formed integrally on the shaft 104 to maintain the shaft 104 and pinion 102 in correct vertical position.

Above flange 116 the shaft 104 carries a gear 118 and a pin 120 provides a driving connection between gear 118 and the shaft 104. Meshing with gear 118 and also contained in cavity 113 is a pinion 122 mounted on the output shaft of a geared electric motor 124 (Figures 1 and 2) secured by screws 126 to an extension of the bracket 38. Operation of the motor 124 alternately in the forward and reverse directions will reciprocate the slide 68 on its base 62. The speed of rotation of shaft 104 is reduced from that of the motor both by virtue of the motor's built-in speed reducing mechanism and by the gears 116, 122 which may be replaced with a pair of gears having a different ratio to alter the speed of reciprocation of the slide. The cavity 113 is closed against the entry of dirt as by a cover 128 secured by fasteners 130 of the well known bayonet type for con-

venient and rapid removal and replacement of the cover. A protective hood 132 is secured to the bracket portion 108, as by means of a clamp 134 and screws 136, to cover the bracket 96 over its entire longitudinal travel (Figures 1, 2 and 4).

The alternating reversal of motor 124 may be effected by various means, that illustrated in Figures 2 and 3 being both efficient and convenient. This means comprises an angle bracket 138 secured by screws 140 to the lateral extension of bracket 38 near the bottom thereof. A pair of limit switches 142 are fastened by screws 144 to the upper surface of the bracket 138. The switches 142 are thus disposed in a position to be actuated by a pair of fingers 146 secured to the upwardly facing surface of slide 68 by screws 148. The fingers 146 trip the switches 142 alternately to operate the motor 124 in the reverse directions. The electrical connections for such operation are well known and do not require further discussion.

In Figure 3 the fingers 146 are shown extending rearwardly exactly perpendicular to the path of travel of the slide 68. It should be noted that they may be set at a substantial angle relative to the positions shown to thus vary the length of travel of the slide. Alternatively, several holes may be provided in the bearing strip 74 to relocate one or both of the fingers 146 to achieve the same result.

As best shown in Figure 5, a tension spring 150 is connected between a spring post 152 screwed into the bottom plate 72 at the left end of slide 68 and a second spring post 154 screwed into the bracket 38 near the right end thereof. The spring 150 thus biases the slide 68 constantly in one direction to eliminate backlash in the reciprocation thereof.

The bracket 38 is formed with a forwardly extending bottom portion 156 (Figures 1, 4 and 5) having a plane horizontal surface 158 on which a second slide base 160 is mounted. The slide base 160 is attached to bracket portion 156 by screws 162 and a locating pin 164 (Figure 5). A slide assembly 166 is mounted on base 160 in the same manner as slide 68 is mounted on slide base 62 and for movement in the same direction. The slide assembly 166 comprises a top plate 168, a bottom plate 170 and a pair of bearing strips 172, all retained in assembled relation by cap screws 174 (Figure 4). Bearing races are also provided, along with bearing rollers 176 and bearing retainers 178. The structure of slide 166 is exactly the same as that of the slide 68 described above and therefore need not be described further. A sealing plate 180 surrounds the slide base 160 and is pressed upwardly against the bottom plate 170 by springs 182 seated in recesses in the bracket portion 156 and retained therein by screws 184 (Figure 5).

As shown in Figure 5 the right end of slide 166 is closed by an end cover plate 186 attached to both top plate 168 and bottom plate 170 by screws 188. The left end, however, is closed by a plate 190 extending a substantial distance above the top plate 168 and attached to top and bottom plates by screws 192 (see also Figure 2).

The bracket portion 156 is formed with a lateral extension 194 (Figures 1 and 5) which is bifurcated (Figures 2 and 14) to accommodate one end of a lever 196. The two arms of extension 194 are pierced by aligned openings to receive centering pins 198 having inwardly directed cone points to engage the opposite, internally conical ends of a bushing 200 upon which the lever 196 is journalled for pivotal movement. The center of each pin 198 is retained precisely in position by a radially directed set screw 202. Screws 204, disposed in the extension 194 parallel to the pins 198 have enlarged heads to engage a portion of the pins 198 to hold them in close contact axially with the bushing 200 (Figures 1 and 14).

The upper end of lever 196 has journalled therein a

stub shaft 206 (Figures 5 and 12) having an integral head portion 208. A pair of rollers 210, 212 are mounted for rotation on the shaft 206 between the head 208 and the lever 196. A radially directed set screw 214 is threaded through one side of lever 196 to hold the shaft 206 and rollers 210 and 212 in axial position. On one side of lever 196 a block 216 is secured on the ledge 94 of the top plate 70 of the slide 68 by means of screws 218. The block 216 presents a hardened wear surface 220 for engagement with the roller 210, while avoiding contact with the second roller 212. On the other side of lever 196, a second block 222 is similarly mounted on ledge 94 and is secured to top plate 70 by screws 224. The block 222 has a hardened surface in engagement with the roller 212 only. Thus there is substantially no clearance which might permit the rollers to move longitudinally of the slide relative to the blocks 216 and 222.

As shown in Figures 5 and 13 a second pair of rollers 226 and 228 are rotatably mounted on the lever 196 intermediate the ends thereof by means of a stub shaft 230. The rollers and the shaft are held in position axially by a radially directed set screw 232 threadedly engaged in one side of the lever 196. A bracket 234 is attached by screws 236 to the end plate 190 of slide 166 and has a hardened wear surface 238 for engagement by the roller 228 (see also Figure 2). The bracket 234 extends beyond the lever 196 and a block 240 is secured to the end of the bracket 234 by one of the screws 236, presenting a surface 242 for engagement by the roller 226 on the opposite side of shaft 230 from the surface 238. Again, no clearance is permitted between the rollers and the surfaces contacted thereby.

It will be evident from the above that as the slide 68 is reciprocated by the motor 124, the blocks 216 and 222 will rock the lever 196. Accordingly the rollers 226 and 228 are rocked in the same direction as the rollers 210 and 212 but on a smaller arc. This reduced rocking motion of rollers 226 and 228 is translated into reciprocation of the slide 166 by bracket 234 and block 240 which are attached to the slide as described above. The contact surfaces 238 and 242 are beveled as shown at 244 (Figures 5 and 6) to avoid interfering with the rocking movement of lever 196.

The rectilinear travel of slide 166 in its reciprocatory movement will be proportionately less than that of slide 68 in the ratio of the distance from the center of the shaft 230 to the center of the pivot 198—200 to the distance from the center of the shaft 206 to the same pivot. In the example shown in the drawing the distance from the center of the shaft 206 to the pivot is five times the distance from the center of the shaft 230 to the pivot. Thus the travel or stroke of the slide 166 will be one-fifth that of the slide 68.

It is a feature of the invention that this ratio is maintained accurately throughout the range of movement of the parts. The hollow bushing 200 and centering pins 198 are employed instead of a conventional shaft because wear of a unitary shaft would cause the center of the pivot opening in lever 196 to be shifted downwardly whereas the construction shown permits wear of the bushing 200 to be compensated for by moving the center pins 198 further inwardly from both ends. Also, the portion of the shaft 230 which carries the rollers 226 and 228 is made slightly eccentric with respect to the portion of the shaft which is journalled in the lever 196. Thus the location of the centers of the rollers can be accurately adjusted by rotating the shaft 230. A screw slot may be provided in the head of the shaft to facilitate this adjustment.

A pair of tapped holes 246 (Figure 2) is provided in the upward extension of end plate 190. If a smaller movement ratio is desired, the bracket 234 may be removed from the position shown and relocated upwardly, the screws 236 occupying the holes 246. In this position the bracket 234 and the block 240 coact with a third

set of rollers 248 and 250 affixed to the lever 196 in the same manner as the other rollers. In the example shown, the center of the stub shaft 252 on which the rollers 248, 250 are mounted is located exactly halfway between the axes of shaft 206 and bushing 200 so that, when these rollers are employed to move the slide 166, the extent of that movement is one-half that of the slide 68.

A third slide base 254 (Figures 4 and 5) is secured on top plate 168 by screws 256 and locating pin 258. The base 254 supports a slide assembly 260 for reciprocating movement in a direction exactly perpendicular to the path of movement of the slide assemblies 68 and 166, that is, perpendicular to the axis of the grinding wheel W. The slide 260 is constructed like the other two slides, having a top plate 262, a bottom plate 264 and a pair of bearing strips 266, all held in assembled relation by screws 268. Bearing races are also provided, along with bearing rollers 270 and bearing retainers 272. A pair of end plates 274, attached to top and bottom plates 262 and 264 by screws 276, close the ends of the slide. A sealing plate 278 surrounds the slide base 254 and is pressed upwardly against the bottom plate 264 by springs 280 seated in recesses in the top plate 168 of slide 166.

As shown in Figure 11, the slide 260 is resiliently biased forwardly by springs 282 seated in recesses in the forward surface of the slide base 254. A headed plug 284 is inserted in the forward end of each spring 282 for engagement by the point of a set screw 286 threaded through the forward side of bottom plate 264.

At the rear end of top plate 262 of slide 260 is formed a ledge 288 whereon a template 290 is secured by means of screws 292 and washers 294 (Figures 5 and 6). The template profile 296 is formed on the forward face thereof for camming engagement with a follower or stylus 298. As shown in Figures 4, 9 and 10 the stylus 298 is held in a horizontal recess in one side of bracket 96 and is retained therein by a clamp 300, screw 302 and washer 304. It will be noted that in Figure 5 the hood 132, the bracket 96 and associated parts are not shown to illustrate the underlying structure more clearly.

The forward end of top plate 262 is formed with a boss 306 (Figure 2) having a circular opening to receive a tool holder 308. A diamond dressing tool 310 directed radially toward the grinding wheel W is mounted in a suitable opening 312 in the tool holder 308 and is retained therein by a set screw 314. The center of the tool 310 which coincides with the center of rotation of the tool holder 308 is aligned with the center of the pivot stud 40. Holder 308 has an integral flange portion 316 which extends a substantial distance to the left of the center of boss 306 as viewed in Figure 6 to lie closely adjacent the forward surface of a similar extension 318 of the boss. The tool holder 308 can thus be set at various degrees of angular adjustment relative to the extension 318 to which it is secured by a screw 320 and a washer 322, the screw 320 passing through an elongated slot 324 (Figure 1) provided in the flange portion 316. The angular position of the tool holder 308 may be measured by a suitable scale 326 inscribed on the outward edge of the flange portion 316 in cooperation with an index or zero mark 328 on the extension 318.

The angular adjustment just described is provided for the purpose of permitting the diamond tool to present its true profile to the inclined grinding wheel in those cases comprising low helix angles and simple thread outlines where tilting of the entire mechanism about the pivot 40 is unnecessary. It is to be understood that when the mechanism is tilted about the pivot 40, the holder 308 is not pivoted, that is, it is set on zero.

In operation, the motor 124, through gears 122, 116 and 102 and rack 109, reciprocates the slide 68 in a path parallel to the grinding wheel axis. The reciprocation of slide 68 through blocks 216 and 222 and rollers 210 and 212 causes the lever 196 to oscillate. The rollers 226 and 228, secured on lever 196 cause reciprocation of

the slide 166 in the same direction as slide 68 but at a reduced rate of speed and over a reduced path of travel. Consequently, the diamond tool 310, being indirectly mounted on slide 166 is traversed over the entire operative peripheral surface of the rotating grinding wheel with a rate of speed and length of stroke reduced from those at which the stylus 298, mounted on the slide 68 is traversed relatively to the template 290. The template 290 is kept in camming engagement with the stylus 298 solely by the forward bias given the slide 260 by the springs 282. Thus the relative motion, in the direction of movement of slide 166, between stylus and template causes the slide 260 to be reciprocated transversely, that is perpendicular to the surface of the grinding wheel. It will be noted that movement of the diamond tool 310 perpendicular to the grinding wheel surface is exactly equal to the lift of the template 290 in the same direction.

In the example shown, the distance from the center of bushing 200 to the center of shaft 206 is five times the distance from the center of bushing 200 to the center of shaft 230. Therefore, if the length of stroke of slide 68 is said to be five inches, the length of stroke of slide 166 will be one inch. Since the template 290 is indirectly mounted on slide 166, it will move one inch in the same direction. Since the stylus 298 is attached to slide 68 by bracket 96, the stylus will move five inches in the same direction. The resultant relative movement, then, between stylus 298 and template 290 will be four inches. Thus the profile 296 formed on the template must be expanded laterally at a ratio of 4:1 relative to the profile to be produced on the grinding wheel by the diamond tool 310. Thus, in the example shown, the 14½ degree flank angle of the standard Acme thread profile on the grinding wheel becomes approximately 46 degrees on the template 290 which completely eliminates the irregular camming action which would otherwise result in prior template-controlled dressing mechanisms.

As noted above, when the rollers 248 and 250 are used to reciprocate the slide 166, the stroke of that slide will be one-half that of the slide 68 and the resultant relative lateral movement between stylus 298 and template 290 will be exactly equal to the lateral movement of the diamond tool 310. This positioning of the rollers therefore leads to direct correspondence in size between template and wheel in both directions and may be employed in cases where the flank angles are 30 degrees and larger. Other locations may be provided on the lever 196 for the rollers which operate the slide 166 for producing other ratios as desired, provided corresponding holes are formed in the end plate 190 for repositioning the bracket 234.

The invention may be embodied in other specific forms without departing from the spirit or essential characteristics thereof. The present embodiments are therefore to be considered in all respects as illustrative and not restrictive the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for dressing a grinding wheel mounted on a predetermined axis comprising, a frame, first, second and third slide assemblies, means mounting said first and second slide assemblies in said frame for movement parallel to the axis of said wheel, means mounting said third slide assembly on said second slide assembly for movement normal to the axis of said wheel, a cam element, a follower element, means mounting one of said elements on said first slide assembly and the other of said elements on said third slide assembly, a dressing tool mounted on said third slide assembly, means resiliently urging said third slide assembly toward the periphery of said wheel to urge said tool into engagement with said wheel and

maintain said cam and follower elements in contact, a lever pivotally mounted adjacent one end on said frame, means connecting said lever adjacent its opposite end to one of said first and second slide assemblies, means pivotally connecting said lever intermediate its ends to the other of said first and said second slide assemblies whereby when said lever is oscillated about its pivotal axis said first and second slide assemblies are reciprocated, the distance and rate of movement of said one slide assembly being greater than that of the other slide assembly.

2. Apparatus for generating a profile of predetermined depth and width on the periphery of a grinding wheel mounted for rotation about a fixed axis comprising, a frame, first, second, and third slide assemblies, means mounting said first and second slide assemblies in said frame for movement in a direction parallel to said axis, means mounting said third slide assembly on said second slide assembly for movement in a direction normal to said axis, a template mounted on said third slide assembly, said template having a contour of the same depth as said predetermined profile and having a width which is a predetermined multiple of the width of said predetermined profile, a stylus mounted on said first slide assembly opposite said template, means resiliently urging said third slide assembly toward said wheel to urge said tool against the periphery of said wheel and urge said template against said stylus, a lever pivotally mounted adjacent one end on said frame, means pivotally connecting said lever adjacent its opposite end to said first slide assembly, means pivotally connecting said lever intermediate its ends to said second slide assembly, and means to cause said lever to oscillate about its pivotal axis to thereby reciprocate said first and second slide assemblies, the distance between the pivotal connections of said lever to the respective first and second slide assemblies and the pivotal axis of said lever being such that the distance travelled by said first slide assembly is said predetermined multiple of the distance travelled by said second slide assembly.

3. Apparatus for dressing a grinding wheel mounted on a predetermined axis comprising a frame, a bracket mounted on said frame for rotation about an axis lying in a plane containing the axis of said wheel, a first slide assembly mounted on said bracket for movement in a direction parallel to said wheel axis and carrying a cam follower, a second slide assembly mounted on said bracket for movement in a direction parallel to said wheel axis, a third slide assembly mounted on said second slide assembly for movement in a direction normal to said wheel axis, a cam and a dressing tool mounted in predetermined relation on said third slide assembly the axis of said tool lying substantially in said plane, means resiliently urging said third slide assembly toward said wheel to urge said cam against said follower and said tool against the periphery of said wheel, and means operative to oscillate said first and second slide assemblies, the distance and rate of movement of said first slide being greater than that of said second slide.

4. Apparatus for dressing a grinding wheel mounted on a predetermined axis comprising a frame, a first slide assembly mounted on said frame for movement in a direction parallel to said axis and carrying a cam follow-

er, a second slide assembly mounted on said frame for movement in a direction parallel to said axis, a third slide assembly mounted on said second slide assembly for movement in a direction normal to said axis, a cam and a dressing tool mounted in predetermined relation on said third slide assembly, means resiliently urging said third slide assembly toward said wheel to urge said cam against said follower and said tool against the periphery of said wheel, a lever pivotally mounted at one end in said frame and engaging said first and second slide assemblies at its opposite end and intermediate its ends, respectively, and a motor operatively connected to oscillate said lever about its pivot axis whereby when said motor is operated said first and second slide assemblies will be oscillated, the distance and rate of movement of said first slide being greater than that of said second slide.

5. Apparatus for dressing a grinding wheel mounted on a predetermined axis comprising a frame, first, second and third slide assemblies, means mounting said first and second slide assemblies on said frame for movement parallel to the axis of said wheel, means mounting said third slide assembly on said second slide assembly for movement normal to the axis of said wheel, a cam element, a follower element, means mounting one of said elements on said first slide assembly and the other of said elements on said third slide assembly, a dressing tool mounted on said third slide assembly, means resiliently urging said third slide assembly toward the periphery of said wheel to urge said tool into engagement with said wheel and maintain said cam and follower elements in contact, a lever assembly pivotally mounted adjacent one end on said frame, pairs of concentric rollers mounted adjacent the opposite end of said lever assembly and intermediate the ends of said lever assembly respectively, means forming wear surfaces on said first and second slide assemblies, respectively, each of said surfaces being adapted to engage one of said rollers, and means for causing said lever assembly to oscillate about its pivotal axis to thereby relatively reciprocate said first and second slide assemblies.

6. The apparatus according to claim 5 together with means for adjusting the position of at least one of said pairs of rollers with respect to the pivotal axis of said lever assembly.

7. The apparatus according to claim 5 wherein at least one of said pairs of rollers is mounted on a pin carried by said lever assembly, the portion of said pin supporting said rollers being eccentric with the portion of the pin carried by the lever assembly whereby rotation of said pin is effective to adjust the distance of the centers of said rollers from the pivotal axis of said lever assembly.
